STORE FRONT SASH

Angus N. McDonald, Detroit, Mich., assignor to
 Detroit Show Case Company, a corporation of
 Michigan

Application September 25, 1931
 Serial No. 565,118

10 Claims. (Cl. 20—56.4)

My invention relates to metal store front construction and particularly to a metal sash for the large plate glass panes used in store fronts.

An object is to provide an improved metal sash assembly for large plate glass panes, such as are used in stores, and a purpose of my invention is the provision of an improved metal sash of this character which is simple, sturdy, inexpensive, and adaptable to artistic forms and which comprises a minimum number of simple, easily manufactured parts that are capable of being readily assembled in position to support the glass pane.

My construction is of that class wherein the fastening devices that secure the sash elements in place are inserted from the rear and are not exposed to view from the front. Fastening elements which are in large part concealed have heretofore been employed in this industry, but an advantage of my invention is that the arrangement and construction is such that these fastening devices can be quickly installed and are positive in their functioning.

My invention has as an object the provision of a construction consisting of few simple parts wherein the holding parts may be made strong to take the strain and the more decorative parts may be made of metal relatively less strong. The parts which constitute my invention are easily transportable in suitable packages without injury. They adapt themselves readily to interfitting assembly. They are of such a character as to be capable of manufacture in a variety of artistic shapes without loss of their advantageous mechanical functioning.

35 A meritorious feature of my invention is that there is associated with the face plate portion of the sash a series of detachable elements which are carried thereby but adjustable lengthwise therewith and which extend underneath the edge 40 of the glass pane and engage the set plate or gutter portion of the sash and are connected therewith by suitable fastening devices to hold the two parts of the sash against the opposite faces of the glass.

45 The above objects and others will more fully appear from the following specifications, appended claims, and accompanying drawing wherein:

Fig. 1 is a perspective of the face plate portion 50 of my metal sash,

Fig. 2 is a perspective of the set plate portion of the sash,

Fig. 3 is a section through one of the supports for the glass pane, and

55 Fig. 4 is a horizontal sectional view through

the assembled sash shown in its supporting relationship to the glass pane.

In the drawing the face plate is indicated generally by the numeral 10. It has a channel shaped bottom portion 12, the lower wall 14 of which is 60 adapted to rest upon a stationary part such as a sill 16. The face plate has along its upper margin a channel indicated generally as 18 which has an inner deflected wall 20 a portion of which bears against the glass pane 22. The glass pane is self 65 supported upon elements 24. These are shown in each of the figures of the drawing. They comprise generally channel shaped metal members which rest upon the sill and which carry a cushioning seat 26 of lead or other suitable material along the upper surface against which the edge of the glass rests.

The set plate or gutter member is indicated generally at 28. It has a base 30 which has an upturned edge 32 that is received within the 75 channel 12 of the face plate and overlies the side wall 14 of the channel 12. This gutter member is formed in such a fashion as to have a channel portion 34 along its upper edge which has an outer side wall 36 that rests against one face of 80 the glass pane. The glass pane is therefore positioned by the wall 36 and the channel 34 and the wall 20 of the channel 18 of the set plate and face plate respectively. The channel 34, due to its formation, provides a groove within the 85 interior of the set plate. This groove is formed between one side wall of the channel and the opposite wall of the set plate.

The bottom of the channel 34 is provided with apertures 38 through which securing means are 90 inserted in a manner hereinafter described to hold the set plate and face plate against the opposite sides of the glass pane.

I provide a plurality of channel shaped elements indicated generally as 40. Each of these 95 elements has a slot 42. This slot is of such a width as to register substantially with the aperture 38 in the channel of the set plate. These channel elements 40 are secured as shown in Figs. 1 and 2 to the face plate. Each channel 100 element 40 has a side wall which is inserted within the channel 18 of the face plate. Due to the deflection of the wall 20 of this channel 18 and the fact that the construction is of sheet metal possessing inherent resilience and that the aperture of the channel is of such a size as to permit the insertion in the side wall of the channel member 40 therein to be frictionally gripped thereby, the channel member 40 is held by the frictional gripping engagement of the side wall 20 of the 110

channel 18 against the side wall of the channel member 40 which is inserted within the channel 18. This is shown in Fig. 1.

The channel elements 40 are arranged in spaced apart relationship lengthwise of the face plate 10 and may be shifted lengthwise to bring them to desired positions therealong. When the device is installed to support a glass pane the set plate 28 is first positioned on the sill and secured by means of screws 44. The glass pane 22 is placed upon the blocks 24, which are arranged at suitable places along the sill. The channel elements 40 are then inserted within the channel 18 of the face plate as shown in Figs. 1 and 2 to be carried thereby and are arranged at the proper intervals and the face plate is then brought into position with the channel elements 40 extending underneath the edge of the glass pane between the supports 24, as shown in Figs. 1 and 2. These channel elements 40 engage in the manner shown in Fig. 4 so that one side wall engages within the groove in the set plate 28. Screws 46 are then inserted through the apertures 38 and threaded into the slots 42 in the channel elements 40. Due to the use of slots in the elements 40 it is readily possible to insert and fasten screws without feeling for the aperture, as would be the case if round apertures similar to 38 were provided in the elements 40. Tightening of the screws 46 draws the channel elements 40 firmly up against the set plate and also draws the face plate channel portion 18 firmly against the face of the glass pane so as to snugly grip the pane between the face plate portion 20 and the set plate flange 36.

Due to providing the channel portions 40 as a separate element as compared with copending application Ser. No. 487,837 of this applicant where these channel portions are integral with the face plate, it is possible to arrange such channel portions relatively along the length of the face plate and it is further possible to provide such channel portions in different metal than that of the face plate. It is frequently desired that the metal of the face plate be of a decorative character which is relatively light in weight and the channel elements 40 take the strain of the screws 46.

A further advantage in having these separate parts is that it is an easy job of manufacture as the parts are more simple in form and, further, the parts may be assembled for shipment in a more convenient package than if the channel elements 40 form an integral part of the face plate 10. The metal sash structure here shown is adaptable to be made in various forms or shapes which conform to a predetermined type of architecture. It may be of modernistic or other design. The functional purposes are served equally regardless of the shape.

I have illustrated a preferred embodiment of my invention in the accompanying drawing but I intend to limit myself only as within the scope of the appended claims, as other embodiments are equally available.

What I claim:

1. In store front construction in combination with a glass pane, a sash assembly comprising a face plate having a part engaging one face of the pane, a set plate having a part engaging the opposite face of the pane, a channel element carried by the face plate and adjustable therealong and extending underneath the edge of the glass pane and engaging with the set plate, and securing means connecting said channel element

to the set plate to hold the set plate and the face plate against opposite faces of the glass pane.

2. In store front construction in combination with a glass pane, a sash assembly comprising a face plate having a part engaging one face of the pane, a set plate having a part engaging the opposite face of the pane, a plurality of channel elements carried by the face plate spaced apart lengthwise thereof and adjustable therealong, each channel element extending underneath the edge of the glass pane, and securing means connecting said channel elements with the set plate to hold the set plate and face plate against opposite faces of the glass pane. 80

3. In store front construction in combination with a glass pane, a sash assembly comprising a face plate having a part engaging one face of the pane, a set plate having a part engaging the opposite face of the pane, a plurality of channel elements arranged spaced apart lengthwise of the face plate, each channel element being frictionally supported by the face plate and being adjustable lengthwise thereof and extending underneath the edge of the glass pane, and securing devices connecting said channel elements with the set plate to hold the set plate and face plate against opposite sides of the glass pane. 95

4. In store front construction in combination with a glass pane, a sash assembly comprising a face plate having a part engaging one face of the pane, a set plate having a part engaging the opposite face of the pane, said face plate provided with a groove on one side of the glass pane, said set plate provided with a groove on the opposite side of the glass pane, a channel element extending underneath the edge of the glass pane and having one side wall engaged within the groove in one plate and the other side wall engaged in the groove in the other plate, and securing means connecting said channel element to the set plate to hold the set plate and face plate against opposite faces of the glass pane. 100

5. In store front construction in combination with a glass pane, a sash assembly comprising a face plate having a part engaging one face of the pane, a set plate having a part engaging the opposite face of the pane, said face plate provided with a groove on one side of the glass pane, said set plate provided with a groove on the opposite side of the glass pane, a channel element extending underneath the edge of the glass pane and having one side wall engaged within the groove in one plate and the other side wall engaged in the groove in the other plate, one of said side walls engaged within the groove in its plate to be frictionally gripped and supported thereby, and securing means connecting said channel element to the set plate to hold the set plate and face plate against opposite faces of the glass pane. 110

6. In store front construction in combination with a glass pane, a sash assembly comprising a face plate having a part engaging one face of the pane, a set plate having a part engaging the opposite face of the pane, said face plate provided with a groove on one side of the glass pane, said set plate provided with a groove on the opposite side of the glass pane, a channel element extending underneath the edge of the glass pane and having one side wall engaged within the groove in one plate and the other side wall engaged in the groove in the other plate, said groove in the face plate being so fashioned as 120

- to grip the side wall of the channel element to support said channel element, and securing means connecting said channel element to the set plate to hold the set plate and face plate against opposite faces of the glass pane. 5
7. In a store front construction, in combination with a glass pane, a sash assembly comprising a face plate having its upper longitudinal margin turned over and forming an inside channel one side wall of which engages the glass pane, a set plate having its upper longitudinal margin turned over forming an outer channel one side wall of which engages the opposite face of the glass pane, a channel element frictionally received within and supported by the channel of the face plate and extending underneath the edge of the glass plate and engaging one side of the channel in the set plate. 10
8. In a store front construction, in combination with a glass pane, a sash assembly comprising a face plate having its upper longitudinal margin turned over and forming an inside channel one side wall of which engages the glass pane, a set plate having its upper longitudinal margin turned over forming an outer channel one side wall of which engages the opposite face of the glass pane, a separate channel element having one side wall received within the channel of the face plate and extending underneath the 15
- edge of the glass pane, and securing means connecting the set plate and said channel element to hold the face plate and the set plate against opposite faces of the said pane. 20
9. In store front construction in combination with a glass pane, a sash assembly comprising a face plate having a part engaging one face of the glass pane and provided with an inside channel element partly defined by said part, a set plate having a part engaging the opposite face of the glass pane, an element adapted to extend underneath the edge of the glass pane and engaged within the channel of the face plate to be supported thereby. 25
10. In store front construction in combination with a glass pane, a sash assembly comprising a face plate having a part engaging one face of the glass pane and forming a gripping element, a set plate having a part engaging the opposite face of the glass pane, a channel element extending underneath the edge of the glass pane and frictionally supported by the said gripping element part of the face plate and the opposite wall of the face plate and adjustable lengthwise along said face plate, and securing means 30 adapted to connect said channel element and set plate to hold the set plate and face plate against opposite faces of the glass pane. 35
